UNITED STATES PATENT OFFICE.

BENJAMIN F. MICKLEY, OF SENECA FALLS, NEW YORK.

NAVIGABLE AEROPLANE.

No. 851,683.

Specification of Letters Patent.

Patented April 30, 1907.

Application filed May 13, 1905. Serial No. 260,252.

To all whom it may concern:

Be it known that I, BENJAMIN F. MICKLEY, of Seneca Falls, in the county of Seneca, in the State of New York, have invented new and useful Improvements in Navigable Aeroplanes, of which the following, taken in connection with the accompanying drawings, is a full, clear, and exact description.

This invention relates to certain improvements in navigable aeroplanes, in which the essential object is to provide mechanism under the control of the operator whereby the machine may be lifted straight up from the ground to any desired height, and then by the same means propelled in any direction.

Another object is to render the machine dirigible by the same lifting and propelling mechanism so that the operator may readily ascend to greater altitudes, travel on a level, or descend gradually to any desired location either against, transversely of or with the wind.

Other objects relating to the specific construction and arrangement of the parts of the machine will be brought out in the following description.

It will be observed upon reference to the following description that the invention relates more particularly in the novel means herein described and illustrated in the accompanying drawing for securing the counter-poising and manipulation of two or more sets of oppositely traveling planes or comparatively thin blades which depend for their lifting and propelling power first—upon their angle of impact with the air; second, their speed of travel whereby the force of such impact is increased or diminished, and third, the relative angles or inclinations from a horizontal at which the oppositely traveling blades or planes are set or adjusted to regulate the upward lift, horizontal travel and oblique ascension or descension. I have therefore, illustrated but generally, and largely diagrammatically, the motive power and auxiliary steering mechanism, as the particular form of such motive power and auxiliary steering mechanism is immaterial, and may be of any form or type desired, the same being outside the scope of the invention as above outlined.

In the drawings—Figures 1 and 2 are respectively a top plan and a side elevation of a navigable aeroplane embodying the features

of my invention showing the planes or blades of each set as disposed at the same angle for lifting the machine vertically or straight up from the ground. Figs. 3, 4, and 5 are sectional views taken respectively on line 6—3—3, Fig. 1, and 4—4 and —5—5—Fig. 3, showing one set of planes in position for propelling the machine horizontally or at such dip or inclination as may be desired.

The means herein illustrated for carrying out the objects stated consists essentially of a comparatively light, yet rigid skeleton frame —1— in which are mounted oppositely disposed pairs of upright rotary drums —2— for receiving, supporting and actuating a pair of endless traveling carriers —3— each of which is provided with a plurality or series of substantially flat thin planes or blades —4— and 4'—.

The frame —1— is made of suitable, light and tenacious metal, such as tubular steel or aluminium of skeleton structure, adapted to present a minimum resistance surface to the air during the ascension and propulsion of the machine and preferably comprises lower and upper substantially horizontal parallel decks —6— and —6'— which are spaced apart and rigidly held in this relation by a series of (in this instance four) vertical sustaining posts or columns —8— upon which the drums —2— are journaled. These sustaining posts or columns —8— are, therefore, parallel and of equal length or height and are located at the corners of an imaginary rectangular parallelogram, thereby retaining the drums —2— in similar relation between the decks —6 and 6'—.

The drums —2— are preferably of the same diameter and each includes a pair of sprocket or equivalent wheels —9— which are spaced apart vertically and are retained in this relation by a sleeve —10— of relatively small diameter to permit the oppositely moving blades or planes to travel close to each other, leaving only sufficient clearance to avoid friction with each other or with the sleeve, thereby enabling the parts to be brought into close compact relation.

It is now obvious that there are two pairs of sprockets —9— at each side of and equidistant from the center of the machine disposed in parallel planes one above the other and those of each pair are connected by an endless chain or belt —11— constituting one of the carriers —3—, whereby positive mo-

tion is transmitted from one drum to the other.

The chains or belts forming the carrier on one side of the machine are connected at regular intervals throughout their lengths by upright tie bars —13— each of which receives and supports two of the blades or planes —4— and —4'— of the lower and upper series respectively, one above the other 5 and has its lower and upper ends provided with suitable anti-friction rollers or bearings —13'— which engage and are guided upon or against suitable lower and upper endless tracks or guides —12— forming parts of the 10 lower and upper decks of the main supporting frame. It, therefore, follows that each carrier —3— is guided upon and between two parallel endless tracks having their ends concentric with the axes of their respective 15 drums to prevent sagging or displacement of the carriers and to resist the weight and impact of the blades against the air while in operation, each track being of substantially the 20 same length and following the line of travel of its carrier —3—.

The lower and upper decks of the main frame are further braced and tied together fore and aft at the longitudinal center of the machine by additional brace bars —14— 25 and sustaining posts —15—, the latter consisting of rotary screws, one at each end of the machine for adjusting and supporting a vertically adjustable slotted intermediate deck —16— having a pair of tracks —16'— 30 which are disposed in the same horizontal plane between and in vertical alinement with the tracks or guides —12— of the lower and upper decks and serve as a means for adjusting the angle of inclination of the lower series 35 of blades —4'— presently described. The central horizontal portions of the inner or adjacent sides of the tracks —16'— are depressed in a plane below that of their outer longitudinal sides and ends and are preferably formed with lengthwise slots registering with similar slots in the deck 16 in which are movable the opposite lengthwise sides of an auxiliary vertically adjustable track —17—. This latter auxiliary track —17— is adjustable 40 vertically independently of the tracks —16'— of the intermediate deck to regulate the angle of the rearwardly traveling blades or planes, and is, therefore, mounted at its ends upon vertical adjusting screws —18—, 45 which in turn, are journaled in and rise from the lower deck of the main supporting frame midway or in substantially its horizontal center and are connected by a suitable chain or belt —19— or equivalent device whereby 50 the same rotary motion is transmitted to both screws simultaneously. In like manner the threaded posts or screws —15— are connected for simultaneous rotation by means of a chain or similar device —20— to 55 raise and lower the tracks —16'— it being

understood that the ends of the intermediate deck —16— and also the ends of the auxiliary track —17— are formed with threaded apertures for receiving and engaging their respective adjusting screws —15— and —18—.

The blades or planes —4— of the upper tier or series are preferably fixed to their respective upright tie bars —13— of carriers —3— with their advancing ends tilted or inclined upwardly at a slight angle from a horizontal so that when they are actuated in the direction indicated by arrows —x— at a greater or less speed of travel their impact with the air will produce a certain lifting power (depending upon the angle and speed of the blades) tending to lift the machine straight up from the ground and to sustain it in a horizontal position while traveling through the air.

The blades —4'— of the lower tier or series are loosely or pivotally attached to their respective tie bars —13— and are, therefore, tilttable to different angles with their advancing ends inclined upwardly and their rear ends trailing or riding upon the tracks 16'— and —17— and spring-pressed downwardly by suitable springs —21— to exert an additional lifting power or to propel the machine horizontally after being lifted to the desired height.

It will be observed that the blades or planes —4— and —4'— on the inner or adjacent sides of the carriers travel in one direction while those on the outer sides of the carriers move in the opposite direction and it is, therefore, apparent that if all of the planes of each series were maintained at the same angle and caused to travel at a suitable speed the machine would be lifted directly upward by reason of the fact that a substantially equal number of blades inclining in opposite directions are traveling in opposite directions, and therefore, the power exerted to lift one end of the machine is balanced by an equal power lifting upon the opposite end, thus poising the machine and lifting it straight up to any desired altitude, the speed of elevation or descent being governed by the speed of travel and angle of the blades of the lower series as regulated by the adjustment of the intermediate deck or tracks —16'— through the medium of the screws —15—. When the machine is thus brought to the desired altitude, it may be propelled or navigated horizontally through the air by simply lowering the track or rails —17— which is effected by the operator through the medium of the chain —19— and screws —18—, thereby causing the blades or planes —4'— on the inner adjacent sides of the carrier —3— to be tilted to a greater angle from a horizontal than those at the outer sides of the carrier, it being understood that the trailing end of each blade or plane —3— is held by its

spring —21— in engagement with the rails —16— and —17— so that when said rails are lowered the advance ends of the tilting blades are thrown upwardly and that when the rails are elevated the blades are moved toward a horizontal position against the action of their respective springs. It is now obvious that by further tilting the blades or planes —4'— of the lower tiers on the inner or adjacent sides of the carriers —3— traveling in one direction so that their advance ends incline upwardly at a greater angle than the blades of the same tiers on the outer sides of the carriers traveling in the opposite direction, the resultant excessive impact of the inner blades against the air will propel the machine in a direction opposite to the direction of travel of the inner or adjacent sides of the carriers and at the same time the remaining blades being disposed at a less angle will operate to maintain the machine at the desired altitude. Or by adjusting the angle of the blades 4'— on the outer sides of the carriers to a greater or less angle the machine will be caused to ascend or descend at the will of the operator by simply raising or lowering the track —16'— through the medium of the screws —15— and connecting chain —20—.

30 Any suitable motive power may be employed for driving the rotary drums 2, but as I do not claim any specific form of motive power, I illustrate the same in Fig. 2 only for the purpose of showing a driving means, and I do not lay claim to any of the matter shown in said view in so far as it relates to the motive power. As illustrated in said view a comparatively narrow platform A is suitably suspended from the frame of the aeroplane having a suitable guard-railing, and on this platform is placed a motor or motors B provided with a chain wheel C in alinement with the chain wheels 22 on the sleeve 10 of the drum 2, and over which a drive chain is adapted to be conducted. From his position on this platform A, the operator will be able to control all the mechanism that operates the air ship, such as the screws employed for adjusting the angle of the aeroplanes etc.

50 It will be observed that by driving the carrier and its aeroplanes at one side at a greater rate of speed than those at the other side I am enabled to guide the machine in any direction, in which case, it would be necessary to drive each carrier by a separate motor. It will also be seen that by providing separate adjustable tracks for the inner and outer sets of planes or blades traveling in opposite directions the machine is rendered navigable and dirigible under all conditions of calm or wind either against a strong head wind or moving with or across swift currents of air by reason of the fact that the planes traveling in one direction are tilted oppositely to those traveling in the reverse direction and

the tiltable planes may be quickly and easily adjusted at any time by the operator to maintain the equipoise of the machine, such control being obvious upon a careful consideration of the travel and adjustability of the planes.

The operation of my invention is clearly set forth in the foregoing description, and while I have shown only two tiers of blades or planes and means for simultaneously adjusting the ends of the tracks —16' and 17, I reserve the right to employ any number of tiers of planes and to use any means for tilting said planes to the same or different angles at any point in their travel and to adjust either end of either track independently. I also reserve the right to connect the blades of two or more tiers so that they may be tilted at the same time in case I employ several tiers.

Having thus described my invention, what I claim and desire to secure by Letters Patent is—

1. An aeroplane comprising a comparatively light supporting frame, two sets of planes each set mounted on an endless carrier, the planes on one side of each carrier traveling in opposite directions and inclined in opposite directions, to the planes on the opposite side whereby the longitudinal thrust of those traveling in one direction is counterbalanced by that of those traveling in the reverse direction, thereby lifting the machine bodily by their impact with the air, and means to actuate said planes.

2. An aeroplane comprising a supporting frame, two sets of planes each set mounted on an endless carrier and the planes at one side of each carrier inclined and traveling in reverse directions and actuating means therefor, each set comprising two series of planes, those of one series being tiltable to different angles toward and from a horizontal position, and means to vary the angle of inclination of the tiltable blades whereby the machine may first be lifted in the air and then propelled.

3. An aeroplane comprising two independent carriers, the carriers having on their opposite sides reversely inclined and oppositely traveling planes, a supporting frame therefor, and means to move said carriers in reverse directions, each carrier being provided with two series of planes one above the other, and traveling in the same direction said planes having their advance ends elevated above their trailing ends.

4. An aeroplane comprising a main supporting frame, a plurality of endless carriers mounted on vertical axes and having planes on one side traveling in one direction, other planes carried by the opposite sides of the carriers and traveling in a reverse direction, said planes being adjustable to and from a horizontal position, separate driving means

for said carriers, and additional means to adjust the planes to and from a horizontal position.

5. An aeroplane comprising two endless carriers mounted on vertical axes and a supporting frame therefor, each carrier having a plurality of planes tilted at an angle from a horizontal, and means to actuate the carriers.

6. An aeroplane comprising a supporting frame, two endless carriers mounted in and upon said frame, a series of planes rigidly attached to each of said carriers to move therewith, a second series of planes movably mounted on each carrier, and means for tilting the movable planes to and from a horizontal position.

7. An aeroplane comprising a supporting frame and two endless carriers revolvably mounted thereon side by side on vertical shafts, means to actuate the carriers whereby adjacent sides are caused to move in the same direction, and a series of planes mounted on each carrier to travel therewith, said planes having their advancing ends tilted upwardly whereby those traveling in opposite directions exert an equal upward lift upon the machine by impact with the air.

8. An aeroplane comprising a supporting frame and two endless carriers revolvably mounted thereon side by side, a series of planes fixedly attached to each carrier and having their advancing ends inclined upwardly, a second series of planes mounted on each carrier and having their advancing ends tilttable upwardly to and from a horizontal position, means to revolve the carriers, and separate means to adjust the advancing ends of the planes of the second series.

9. An aeroplane comprising a comparatively light supporting frame, opposite pairs of vertically disposed drums revolvably mounted on the frame, an endless traveling carrier, mounted upon and actuated by each pair of drums, two series of planes mounted on each carrier one above the other, means to 45 rotate the drums to cause the adjacent sides of said carriers and the planes thereon to move in the same direction, the planes of one series being adjustable toward and from a horizontal position, and means to adjust said 50 adjustable planes to different angles during the revolution of the carriers.

10. An aeroplane comprising a frame, a pair of endless tracks adjustable vertically on the frame, means to adjust said tracks, 55 endless carriers revolvably mounted on the frame, one for each track, and a series of inclined planes attached to and actuated by each of the carriers and trailing upon said tracks, whereby the adjustment of the tracks 60 varies the inclination of the planes.

11. An aeroplane comprising a frame and revoluble endless carriers mounted side by side on the frame, means to actuate the carriers whereby their adjacent sides are caused to 65 travel in the same direction, a series of inclined planes on each carrier and traveling therewith, an adjustable track operable to vary the inclination of the planes while traveling, and means to adjust said track. 70

In witness whereof I have hereunto set my hand this 6th day of May 1905.
